UNITED STATES PATENT OFFICE.

WARD SPENCER SMITH, OF LONG BEACH, CALIFORNIA.

CONCRETE FORM.

Application filed April 29, 1924. Serial No. 709,787.

This invention relates to improvements in concrete forms and more particularly has to do with forms utilized in the erection of monolithic cellular structures.

5 Since the invention is particularly applicable to forms used in the construction of concrete cell blocks for mausoleums, I will describe the forms as put to this specific use. However, the confinement of the description to this particular embodiment is in no way intended as limiting the inventions thereto.

Certain peculiar difficulties arise in connection with the construction of cell blocks 15 which exist nowhere else in the field of concrete engineering, and these difficulties have been of sufficient magnitude to preclude widespread construction of multicell mausoleums, although it is accepted by many that 20 the form of burial provided by this type of structure is more desirable, from many standpoints, than cremation or earth burial.

For instance, there must be used a plurality of core forms to provide the cell voids 25 or crypts, and since the cells are to be of substantially uniform cross section throughout their length, and since the cores can only be withdrawn through the cells mouths, the core forms must be inwardly collapsible 30 and withdrawable through one end of the cell void. While it is further considered that the stripping of the inner end gate of the core from the rear cell wall must be accomplished from within the cell, it is self evident that it is no small problem to provide 35 core forms having desirable collapsible characteristics and yet, when erected, offering proper resistance to the very considerable collapsing and wracking strains which are

40 imposed upon them during the pouring and setting of the concrete. To secure proper form rigidity, it has previously been found necessary to fill the interior of the core with nailed cross bracing, both diagonal and horizontal; but such an expedient is not only 45 costly in time and material consumed, but is also destructive to the forms, since, if any time is to be made in stripping the cell walls, the braces must be torn loose hurriedly and 50 without taking any special precautions to guard against damage to the form walls.

Therefore it is among the objects of my invention to provide a collapsible core form capable of being set up and knocked down 55 with little effort and in minimum time, and

which, when assembled, offers proper resistance to strains imposed thereon. This I accomplish without the use of internal diagonal braces nailed within the core. Furthermore, my core may be readily collapsed, 60 stripped from the cell walls and withdrawn through the cell mouths without causing damage to any of the form parts or bracings, and without unduly marring the walls of the cells from which they are withdrawn. 65 Even disregarding the great advantage my form offers in speed of erection and stripping, the single fact that the life of the form is comparatively long—by reason of the method of assembly and bracing employed—70 is one of great importance and value, for the forms may be used repeatedly and without constant attention and repair. It is well recognized that time and material loss in form replacement and repair exists as one 75 of the principal factors in the ultimate cost of concrete construction and, when close figuring is done, often means the difference between profit and loss to the contractor.

As the cell blocks must be built up tier 80 by tier, it is of some difficulty to so arrange the several core forms in each tier that they are axially parallel and so the partition walls to be poured will plumb up or come in exact vertical alinement with the partitions below. Such alinement is necessary, 85 not only from the standpoint of sightliness and proper imposition and transfer of load, but also to insure that the facing strips of ornamental stone, with which the cell openings are ordinarily outlined, may be interchangeable and may be cut to size at the factory and set in place on the job without the requirement of special fitting.

I have provided forms which may be 95 quickly set up with the assurance that they are in proper relative position with each other and with the cell block beneath, and the core forms and outer wall forms are tied in a manner to preserve such alinement during 100 the pouring and setting of the concrete.

My invention has many other objects and features of novelty, certain of which will be set forth to better advantage in the following detailed description, reference being had 105 to the accompanying drawings, in which

Figure 1 is a perspective view of a typical cell block as constructed with my forms.

Fig. 2 is a fragmentary, enlarged perspective showing the enlargement of the cell 110

mouth to receive a sealing slab, such enlargement not being illustrated in Figure 1, due to the relatively small scale of that drawing.

5 Fig. 3 is a top plan view of a cell block diagrammatically showing my core forms—with covers removed—secured together by the front plate or fence.

10 Fig. 4 is an enlarged fragmentary elevation of the front plate or fence.

Fig. 5 is a view similar to Figure 2, but showing the core forms with their covers in place and showing the side and back wall form plates bolted up to the fence.

15 Fig. 6 is a front elevation of Figure 5.

Fig. 7 is an enlarged vertical section on line 7—7 of Figure 5.

20 Fig. 8 is an enlarged plan view similar to a fragment of Figure 5 but showing the core covers removed.

Fig. 9 is a vertical section on line 9—9 of Figure 8, but showing the core cover and tie rods in place.

25 Fig. 10 is a section on line 10—10 of Figure 9.

Fig. 11 is an enlarged section on line 11—11 of Figure 10; and

30 Fig. 12 is a face view of a newly formed cell after the front plate has been removed and before the core has been collapsed and withdrawn.

35 In Figure 1 is illustrated a cell block C having base B, side walls S, rear wall R, top T, horizontal partition H and vertical partitions V; partitions H and V dividing the block into axially parallel cell voids or crypts A. Preferably, the mouths of the cells are slightly enlarged to provide recesses 10 for receiving a sealing slab (not shown) 40 which is to be cemented in after a burial.

45 It will be understood that mausoleum cell blocks usually contain six or more tiers of cells, each tier being 20 or more cells wide, but it will serve my purpose to describe the relatively small cell block shown in Figure 1, as the forms and the procedure of erection and stripping are identical irrespective of the size of the mausoleum, except that large structures require jointed front 50 and rear form plates.

55 It will also be understood that I provide ducts throughout the structure to provide a slow circulation of air through the cell, but since these ducts are not a part of this invention, I have not shown nor described them.

60 The rectangular cell block in Figure 1 is shown prepared to receive an additional tier of crypts, there being provided wire loops L which extend upwardly from the upper face of top T and in vertical alinement with vertical partitions V, and the pointed pins or anchoring nails P and P' which extend upwardly from top T near the front and rear, respectively, thereof. Loops L are

preferably placed about midway between front and rear faces of the block while anchors P and P' are preferably approximately in alinement with the longitudinal axes of cells A and are spaced from the front and rear of the block a proper distance to line up with certain of the core form members to be hereinafter described. As will be later evident, loops L and anchors P, P' need not be exactly located as they will perform their function if positioned anywhere within certain relatively large areas. 70 75

I will now describe the elements and make-up of a typical collapsible core form generally indicated at F. Referring to Figures 8 to 11, inclusive, it will be seen that form F is made up of sides 11, cover 12, end gate 13, and spreader 14. Sides 11 have vertical battens 15 which are so positioned that when cover 12 is in place, said battens 80 lie close to the horizontal battens 16 of the cover. The upper ends of battens 16 are chamfered at 17 and 18, respectively, and the cover extends beyond the ends of battens 16 to provide for engagement between the cover extensions and the upper edges of sides 11, as clearly shown in Figure 10. 90

Fig. 13 has a central vertical batten 19, preferably of wood, and two vertical edge battens 20, preferably of metal. Central batten 19 supports a pull ring or loop 21, while battens 20 are provided with threaded holes 22 adapted to receive removable bolts 23 which extend through bores 24 in the rearmost battens 15^a. By reason of the predetermined location of holes 22 and 24, end gate 13 with bolts 23 serves as a gage to properly space sides 11 at their rearward ends, and due to the bolted connection between end gate and sides, these members 100 105 act as mutual supports to hold them against collapse. Spreaders 14 are made up of side rails 25, spacers 26 on top the rails, and nailing or anchoring strips 27 and 27^a across the bottom of the rails near the front and rear thereof, respectively. Spreaders 14 are of such width as to engage battens 15 when the side walls 11 are properly spaced. 110

The ends of battens 15 and 16 overlap as illustrated in Figure 11, and holes 28 provided through these overlapping portions are in axial alinement throughout, in order that they may receive a common tie rod 29 at each side of the core form. These holes are also in register with apertures 30 in 120 front plate or fence 31 (see Figure 4). 115

Plate 31 is adapted to define the front face of the top slab to be poured and the front face of the vertical partition which is to be formed between side walls of adjacent cores; 125 to support the forward end of side walls 11; and to act as a gage board for properly spacing the several core forms and for positioning said forms in vertical alinement with underlying cells. The plate is made up 130

of horizontally extending upper and lower rails 32 and 33, respectively, vertical plates 34 for closing off the voids 35 between adjacent core forms (see Figures 3 and 8), vertical braces 36 bolted to plates 34, and diagonal braces 37 bolted to adjacent braces 36.

5 Bolts 38 are adapted to removably clamp fence 31 to the foremost vertical battens 15, the registering bolt holes in said fence and 10 battens being so located that bolts 38 serve to properly space the forward ends of sides 11, both of each individual core forms and of adjacent forms.

In preparing to set forms, wires 39 are 15 first looped through loops L and are then laid out on top the cell block so their free ends extend straight back to rear wall R. The end gate and sides of all the individual core forms are assembled by the proper insertion 20 of bolts 23 (this assembly taking place on top block C) and spreaders 14 are dropped between sides 11 but are not yet driven down on anchors P, P'. During this assembly side walls 11 are roughly lined up 25 with underlying partitions V and the forward ends of the sides are roughly lined up with the front face of block C.

A gage board 40 (Figure 3) is then used to properly space the rear ends of the forms 30 and to line up said rear ends with the underlying cell voids A. Board 40 has a central gage marking and also markings 41 which are horizontally spaced a distance equal to the predetermined center to center distance 35 of the cell voids. End gates 13 have center marks (not shown) on their outer faces. Gage board 40 is lightly nailed to the two center core forms so the center to center markings on the board are coincident or in 40 vertical alignment with the center marks on end gates 13. The two forms are then shifted along the top of the block until the center of board 40 lies in vertical alignment with the center of block C, the latter center 45 being marked in any suitable manner on the foundation or on the rear walls of the block. Spreaders 14 of the two forms are then driven down so anchoring pins or nails P' enter nailing strips 27 to fix the rear end 50 position of the cores. The remaining forms are then lined up with their centers in vertical alignment with the center to center markings on the gage board, and their respective spreaders anchored on underlying pins P'. 55 Gage boards 40 may then be removed.

Fence 31 is then attached to sides 11 of the two center forms by bolt 38, and a center marking 42 provided on the fence is lined up 60 with the center line of block C, whereupon the nailing strip 27 of the spreaders in these two forms are driven down upon nails P. The remaining core forms are then secured to fence 31 by bolts 38, but the upper course bolts are not fully taken up at this time.

65 All the forms being then in axial parallelism

and in vertical alignment with the cell voids below (since the forms of said cell voids were set up in the above described manner) nailing strips 27 are driven down on nails P to removably secure all the forms in this 70 predetermined relation. Covers 12 are then laid over the tops of the forms; tie rods 29 are thrust through holes 30 in fence 31 and registering holes 28 in battens 15 and 16; and all bolts 38 are fully taken up.

75 Spreaders 14 serve to hold the lower portions of sides 11 against collapse while rods 29 tie the cover and sides in a manner to prevent such collapse at the top of the forms, no other type of internal bracing, such as 80 diagonally extending cross bars, being needed to resist strains of load, wrack or collapse. It will also be noted that the major portion of the weight of the concrete slab to be poured on cover 12 is transferred to 85 top T through battens 16, rods 29 and battens 15; rather than through the extensions of the cover where they bear on the upper edges of sides 11. Should the latter condition exist, the edges of the cover and sides 90 would soon yield to the strain and break away, while by my method of connection and weight transfer, the thinner portions of cover and sides need not be subjected to overloading or abuse.

95 In view of the chamfering 17 (which chamfering is provided for a purpose to be later described), it will be seen that bearing cannot be secured between the cover and ends of battens 15, making it all the more desirable that tie rods 29 be used to transfer the strains from batten to batten.

Horizontal strips 43 (Figures 5, 9 and 12) are then laid on top covers 12 at a point adjacent fence 31, and vertical strips 44 (Figures 8 and 12) are laid along sides 11 and in the vertical plane 43. These strips are for the purpose of forming sockets 10 as illustrated in Figure 2.

100 Front plate 31 is, of course, suspended in position by reason of its bolted connection with the cores, and the plate extends above top T a distance equal to the thickness of the top slab to be poured. Side plates 46 and rear plate 47 (Figures 5, 7, 8 and 9) which 110 are supported in a manner now to be described, extend upwardly a distance equal to the upward extension of plate 31, and the upward extensions of the four plates thus function as top slab defining walls as 115 well as forming the end boundaries of the vertical walls to be poured.

Rear plate 47 has vertically extending battens 49 which project below the lower edge of the plate proper, (Figure 7) while side 120 plates 46 have battens 50 which extend similarly below their plates. Rear plate 47 overlaps the rear face of wall R at 51, and the lower edge of the plate rests on bars or rods 52 which are cast in and extend from said 125

wall R. Bars 52 are so vertically spaced from the top of the block that they bring the upper edge of plate 47 into the horizontal plane of the upper edge of front plate 31. The free ends of wire 39 are then passed through holes 53 in plate 47 (Figures 7 and 8) which are arranged on opposite sides of battens 49, and are then twisted about said battens to hold the plate from tilting outwardly from the top; while wires 39^a, which correspond to wires 39 except that they were cast in the underlying tier, are twisted about the lower extremities of battens 49. Wires 39 and 39^a hold the rear plate against separative movement from wall R and from end gates 13.

Side plates 46 rest on bars 54, similarly to the resting of plates 47 on bars 52, and the opposite ends of plates 46 are bolted to front plate 31 and rear plate 47 at 55 and 56, respectively (Figure 5). Thus all the core and plate forms are tied together and are held in predetermined relation both with each other and with cell block C. Wires 39 are especially adaptable to the purpose illustrated in that they may be taken up with a twisting tool in order to slightly incline plates 47 towards forms F to compensate for slight outward movement of the plate when concrete is poured and tamped.

With the forms in place, suitable reinforcements such as is shown at 57 in Figures 8 and 9 may be inserted in the voids and suitably attached to reinforcing members which may project upwardly from the block below, and bars 58 (Figure 7) are inserted through suitable apertures in plate 47 and are caused to project into the void between said plate and the ends of cores F. The holes through which the bars extend are accurately located with respect to the top of the plate, so when the forms are stripped from the structure, bars 58 will project from the newly formed rear wall in position to function in the form setting operation of the next higher tier, after the manner described in connection with plate 47 and bars 52.

After the concrete has been poured and has partially set, the forms are stripped in the following manner: Tie rods 29 are withdrawn, bolts 38 and 55 are removed, and the entire front plate 31 stripped from the structure, the front face of the cell then presenting the appearance illustrated in Fig. 12. A bar is then inserted beneath nailing strips 27, and the spreaders 14 pried loose from nails P and P', whereupon the spreaders may be withdrawn through the cell mouth. A workman then enters the crypt and removes bolts 60 to free sides 11 from end gate 13. Suitable tools are entered in holes or sockets 60 in battens 15^a (Figure 12), and the lower ends of sides 11 are rocked inwardly and away from the side walls of the cell as indicated in dotted lines of Figure 12, the

chamfering 17 and 18 allowing such relative movement between sides 11 and cover 12. Were it not for the provision of the chamfered ends, it will be seen that the ends of battens 15 and 16 would interfere with such movement of sides 11.

Covers 12 are pried loose from the top wall of the cell and then withdrawn; whereupon a pull rod is hooked into ring 21 enabling a workman to pull the end gate loose from the rear wall of the cell.

As fast as the cores are collapsed and withdrawn, they may be erected on another cell block which is to have an additional tier. Bolts 56 are removed and wires 39, 39^a un-twisted, whereupon the side and rear plates may be stripped from their walls, it being necessary, of course, to move said plates horizontally to clear them from bars 58.

It will be understood that the drawings and description are to be considered merely as illustrative of the invention and not as restrictive on the broader claims appended hereto, for certain changes in structure, design, arrangement and connecting means may be made, without departing from the spirit and scope of such claims.

I claim:

1. A collapsible core for the construction of monolithic cellular structures, including side walls, an end gate, a removable spreader adapted to engage the side walls near their lower edges, a removable cover, and removable means for securing the cover to the side walls in a manner to prevent their relative displacement.

2. A collapsible core for the construction of monolithic cellular structures, including side walls, an end gate secured to the side walls from within the core, a removable spreader adapted to engage the side walls near their lower edges, a removable cover, and removable means for securing the cover to the side walls in a manner to prevent their relative displacement.

3. A collapsible core for the construction of monolithic cellular structures, including side walls, an end gate, a removable spreader adapted to engage the side walls near their lower edges, said spreader consisting of spaced side rails engageable with opposite side walls of the core, and spacers joining the side rails; a removable cover, and removable means for securing the cover to the side walls in a manner to prevent their relative displacement.

4. A collapsible core for the construction of monolithic cellular structures, including side walls, an end gate, a removable spreader adapted to engage the side walls near their lower edges, said spreader consisting of spaced side rails engageable with opposite side walls of the core, and spacers joining the side rails; nailing strips on the spreader, a removable cover, and removable means

for securing the cover to the side walls in a manner to prevent their relative displacement.

5. A collapsible core for the construction of monolithic cellular structures, including side walls, vertically arranged internal battens on the side walls, an end gate, removable spreader means adapted to engage the side walls near their lower edges, a removable cover, horizontal battens on the inner face of the cover, the battens on the side walls and cover having overlapping portions, and removable means engageable with said portions for securing the cover to the 10 side walls in a manner to prevent their relative displacement.

6. A collapsible core for the construction of monolithic cellular structures, including side walls, vertically arranged internal battens on the side walls, an end gate, removable spreader means adapted to engage the side walls near their lower edges, a removable cover, horizontal battens on the inner face of the cover, the battens on the side 20 walls and cover having overlapping portions, removable tie rods passing through registering holes in the overlapping portions and adapted to secure the cover to the side walls in a manner to prevent their relative displacement.

7. A collapsible core for the construction of monolithic cellular structures, including side walls, vertically arranged internal battens on the side walls, an end gate secured to the side walls from within the core, removable spreader means adapted to engage the side walls near their lower edges, a removable cover, horizontal battens on the inner face of the cover, the battens on the side 30 walls and cover having overlapping portions, and removable means engageable with said portions for securing the cover to the side walls in a manner to prevent their relative displacement.

45. 8. A collapsible core for the construction of monolithic cellular structures, including side walls, vertically arranged internal battens on the side walls, an end gate, removable spreader means adapted to engage the side walls near their lower edges, a removable cover, horizontal battens on the inner face of the cover, the battens on the side walls and cover having overlapping portions, the ends of the overlapping portions being 50 chamfered; and removable means engageable with said portions for securing the cover to the side walls in a manner to prevent their relative displacement.

60. 9. In a collapsible form for the construction of monolithic cellular structures, a series of horizontally spaced collapsible cores, a front plate extending along the front of and

secured to the cores, a rear plate extending across the rear ends of the core, and side plates bolted at opposite extremities to the 65 front and rear plates, all of said plates extending above the core tops; certain of said cores embodying side walls, an end gate secured to the side walls from within the core, a removable spreader adapted to engage the 70 side walls near their lower edges, a removable cover, and removable means for securing the cover to the side walls in a manner to prevent their relative displacement.

10. In a collapsible form for the construction of monolithic cellular structures, a series of horizontally spaced collapsible cores, a front plate extending along the front of and secured to the cores, a rear plate extending across the rear ends of the core, and side 80 plates bolted at opposite extremities to the front and rear plates, all of said plates extending above the core tops, certain of said cores embodying side walls, vertically arranged internal battens on the side walls, an 85 end gate secured to the side walls from within the core, removable spreader means adapted to engage the side walls near their lower edges, a removable cover, horizontal battens on the inner face of the cover, the battens on the side walls and cover having overlapping portions, and removable means engageable with said portions for securing the cover to the side walls in a manner to prevent their 90 relative displacement.

11. A collapsible core for the construction of monolithic cellular structures, including side walls, a cover removably secured to the side walls at their upper edges, a removable spreader adapted to engage the 100 side walls near their lower edges, and downwardly facing nailing strips on the spreader, the lower faces of said nailing strips being approximately in horizontal plane of the lower edges of the side walls.

12. In a collapsible form for the construction of monolithic cellular structures, a series of horizontally spaced collapsible cores, a front plate extending along the front of and secured to the cores, a rear plate extending 110 across the rear ends of the core, and side plates bolted at opposite extremities to the front and rear plates, all of said plates extending above the core tops, certain of said cores embodying side walls, a removable spreader adapted to engage the side walls near their lower edges, a removable cover, and removable means for securing the cover to the side walls in a manner to prevent their 115 relative displacement.

In witness that I claim the foregoing I have hereunto subscribed my name this 12th day of April 1924.

WARD SPENCER SMITH.
